INVENTOR
James B. Baker
BY
Charles H. Wilson
ATTORNEY

UNITED STATES PATENT OFFICE.

JAMES B. BAKER, OF NEW YORK, N. Y.; M. LINDSAY BAKER AND GUARANTY TRUST COMPANY OF NEW YORK EXECUTORS OF SAID JAMES B. BAKER, DECEASED.

PICTURE HANGING ATTACHMENT.

Application filed January 15, 1916, Serial No. 72,190. Renewed June 5, 1922. Serial No. 566,191.

To all whom it may concern:

Be it known that I, JAMES B. BAKER, residing at New York, in the county of New York and State of New York, have invented 5 certain new and useful Improvements in Picture Hanging Attachments, of which the following is a specification.

This invention relates to a picture hanging attachment.

10 The particular object of the invention is to provide a simple and inexpensive device whereby a picture hanging upon a wall may be quickly and easily adjusted to hang in a proper position.

15 A more specific object is to provide devices which may be connected at opposite sides of the picture frame, the supporting cords of the frame being connected to said devices, and said devices comprising adjustable parts 20 by means of which one side or the other of the frame may be raised or lowered.

Other objects and aims of the invention, more or less specific than those referred to above, will be in part obvious and in part 25 pointed out in the course of the following description of the elements, combinations, arrangements of parts and applications of principles, constituting the invention; and the scope of protection contemplated will be 30 indicated in the appended claims.

In the accompanying drawings which are to be taken as a part of this specification, and in which I have shown a merely preferred form of embodiment of the invention:

Figure 1 is a perspective view of a device constructed in accordance with the provisions of this invention.

Figure 2 is a rear view of a picture frame 40 showing a pair of the devices of Fig. 1 connected thereto and illustrating the supporting cords connected to said devices.

Referring to the drawings for a detailed description of the construction illustrated 45 therein the reference character L indicates a rod preferably of metal, said rod being threaded for a part of or throughout its length. The opposite ends of the rod are formed with enlargements, as 1 and 2.

50 A threaded sleeve G is fitted upon the rod L, rotatable for longitudinal adjustment along said rod. The opposite ends of the sleeve are formed with annular flanges 3.

The enlargement 1 at the upper end of the 55 rod prevents detachment of the sleeve from

the upper end of the rod, while the enlargement 2 at the lower end of the rod prevents detachment of the sleeve from said lower end.

In order to connect the device to the picture frame, a screw-eye, or the like, 4 is provided, the eye portion being disposed to loosely encircle the intermediate part of the sleeve G.

The enlargement 1 at the upper end of the 65 rod is provided with a suitable aperture 5 through which the supporting cord, as 6, in Fig. 2 may be connected.

In order to provide for a quick and efficient attachment of the supporting cord, 70 however, an auxiliary attaching device H is provided. This attaching device comprises simply a piece of wire bent into a loop having its opposite ends overlapping and hook-shaped as shown. In order to attach the 75 picture frame supporting cord within the wire loop, said cord is slipped in between thelapping portions of the loop and twisted upon itself as shown in Fig. 1.

In use the device is attached to the picture 80 frame by inserting the screw-eye 4 into the frame in the usual manner. The cords 6 may be attached either before or after the screw-eyes are inserted.

After the picture is hung, one side or the 85 other may be raised or lowered by simply rotating the sleeve about the rod.

The operation of the devices in each instance is the same. The flanges 3 of Fig. 1 serve to retain the rod against undue longitudinal movement through the screw-eye at 90 all times.

It will be apparent that although two separate supporting cords 6 are shown in Fig. 2, it is nevertheless obvious that a single 95 cord may be employed if desired, in which instance the cord would be simply looped over a single picture hanger 10, in the usual manner and the opposite ends would be connected to the devices upon the picture frame. 100

It is also obvious that in some cases a single device of this invention may be employed in the support of a picture frame.

As many changes could be made in this construction without departing from the 105 scope of the following claims, it is intended that all matter contained in the above description or shown in the accompanying drawing shall be interpreted as illustrative only and not in a limiting sense. 110

Having thus described my invention what I claim as new and desire to secure by Letters Patent is:

- 5 1. In a device of the class described, a threaded rod adapted for attachment to a picture cord, a double shouldered sleeve threaded upon said rod, and a member adapted to be fixed to a picture frame having a part which encircles said sleeve between the shoulders thereof.
- 10 2. In a device of the class described, a threaded rod, one end of which is adapted to be attached to a picture cord, a sleeve

threadedly mounted upon said rod, said sleeve being provided with a reduced portion, and a member adapted to be fastened to a picture frame, having an eye which encircles the reduced portion of said sleeve and is rotatively engaged therewith.

In testimony whereof I affix my signature in the presence of two witnesses.

JAMES B. BAKER.

Witnesses:

MARIE A. JONES,
FRED EVANS.
